GLASS EDGE WORKING MACHINE

James C. Ogle and James F. Jordan, Brackenridge, Pa., assignors to Libbey-Owens-Ford Glass Company, Toledo, Ohio, a corporation of Ohio

Application June 15, 1949, Serial No. 99,218

10 Claims. (Cl. 51—101)

1

The present invention relates broadly to a grinding machine for working the edges of plates of glass or other materials and more particularly to an improved apparatus for edge grinding and/or beveling plates to a predetermined contour.

Although it is to be expressly understood that the grinding machine herein provided is not limited to any specific use, it has been designed primarily for and is of especial utility in the edging of so-called glass mirror plates which are used in the manufacture of rear view mirrors for automotive vehicles and the like. Therefore, while the invention will be more particularly hereinafter described in connection with the edging and/or beveling of glass plates, it may be also used for working the edges of plates of other materials.

An important object of the invention is the provision of a grinding apparatus of novel and improved construction for finish edging and/or beveling plates of glass or other materials rapidly, accurately and economically and with a minimum of handling and also a minimum amount of effort and attention on the part of the operator whereby uniformly contour ground plates with well finished surfaces may be secured.

Another important object of the invention is the provision of a grinding apparatus particularly adapted for working the rough edges of glass blanks of different sizes and/or differing contours to a predetermined outline and with a desired smoothness of finish, while simultaneously producing a ground bevel along the edges of the blanks if desired.

Another object of the invention is the provision of grinding apparatus embodying a novel form of work holder for supporting and firmly securing the glass plates in position to be operated upon and being of such construction that the edges of the plates may be simultaneously contour ground and beveled without the necessity of removing them from the work holder or changing the relative position thereof.

Another object of the invention is the provision of grinding apparatus embodying a pair of grinding units operating about substantially vertical axes together with a work holder rotatably mounted between the grinding units for supporting the glass plate to be ground in a substantially horizontal position, together with means for automatically controlling the rotation of the work holder and the movement of the grinding units toward and away therefrom.

Another object of the invention is the provi-

2

sion of a grinding apparatus embodying a vacuum system associated with the rotatable work holder to secure the glass plate thereon, and a semi-automatic control system manually operable after each grinding operation to first disconnect and subsequently connect the vacuum system to the work holder before starting the rotation of said work holder for the next grinding cycle.

10 Another object of the invention is the provision of a grinding apparatus embodying a template for controlling the movement of the grinding units relative to the glass plate during grinding in such a way that the amount of material removed from the edges thereof is definitely and automatically controlled and is not dependent upon the skill of an operator.

A further object of the invention is the provision of a grinding apparatus comprising a pair of movable grinding units and a rotatable work holder located between said grinding units and having a template associated therewith, manually operable means being provided to move the grinding units into engagement with the template to start the grinding operation and mechanically operable for movement out of engagement with the said template to stop the grinding operation.

30 A further object of the invention is the provision of a grinding apparatus embodying a pair of movable grinding units and a rotatable work holder having a template associated therewith, and which apparatus further includes a power driven cam means, and a semi-automatic control system manually operable to start rotation of the work holder and cam means, said cam means causing movement of the grinding units into and out of engagement with the template at the beginning and end of the grinding cycle and further acting to automatically open the 35 said control system when the grinding units have been moved out of engagement with the template to bring the machine to a stop.

40 A further object of the invention is the provision of a grinding apparatus which embodies a pair of movable grinding units and a rotatable work holder interposed between the grinding units and having a template associated therewith, and in which means is provided for reciprocally moving said grinding units with respect to the work holder, together with a vacuum system associated with the work holder for securing the work thereon, manually operable means for controlling the vacuum system and for 45 preventing rotation of the work holder and

movement of the grinding units into engagement with the template until the work is vacuously secured on the work holder, and means for automatically stopping rotation of the work holder when the grinding units have been moved out of engagement with the template.

A still further object of the invention is the provision of a grinding apparatus comprising a pair of movable grinding units and a rotatable work holder having a template associated therewith, a vacuum system associated with the work holder for securing the work thereon, a control cam for the grinding units, power means for driving the work holder and control cam at a different ratio of speed, and a semi-automatic control system manually operable to initially disconnect and then connect the vacuum system to the work holder after each grinding cycle and prior to the beginning of the next grinding cycle, said control cam being adapted to move the grinding units into engagement with the template while the same is rotating and to remove said units from engagement with said template when the grinding cycle has been completed, the said control cam acting to automatically open the control system when it has caused movement of the grinding units out of engagement with the said template to bring the machine to a stop.

A still further object of the invention is the provision of a grinding apparatus embodying grinding wheels rotatable about substantially vertical axes, a work holder being rotatably mounted between the grinding wheels for supporting the plate to be ground in a substantially horizontal position, with means for moving the grinding wheels in unison toward the plate and for controlling the time they are in engagement with the said plate so that during the grinding cycle established for the apparatus, the plate will be rotated more than one complete revolution, thereby effecting an overlap of grinding action and assuring that the desired pattern will be reproduced without any roughness appearing at the initial point of grinding.

Other objects and advantages of the invention will become more apparent during the course of the following description, when taken in connection with the accompanying drawings.

In the drawings, wherein like numerals are employed to designate like parts throughout the same:

Fig. 1 is a front elevation of an edge grinding machine constructed in accordance with the present invention;

Fig. 2 is a detail view of the controls of the machine;

Fig. 3 is an end view of the machine;

Fig. 4 is a perspective view of the work supporting means showing a rough glass blank to be ground carried thereby;

Fig. 5 is a perspective view of a finished glass plate;

Fig. 6 is a diagrammatic view illustrating the machine operation;

Fig. 6A is a diagrammatic view showing the relative positions of the two cams which control the inward and outward movements of the grinding units relative to the work holder;

Fig. 7 is a plan view of the machine;

Fig. 8 is a horizontal section taken substantially on line 8-8 of Fig. 1;

Fig. 9 is a view similar to Fig. 8, but showing the machine control elements arranged at a midway point in their operating cycle;

Fig. 10 is a detail section taken substantially on line 10-10 of Fig. 9;

Fig. 11 is a detail section taken substantially on line 11-11 of Fig. 9;

Fig. 12 is a detail section taken substantially on line 12-12 of Fig. 9;

Fig. 13 is a top view, partly in section of a portion of the cam following mechanism;

Fig. 14 is an enlarged vertical section taken substantially on line 14-14 of Fig. 3;

Fig. 15 is a detail section taken substantially on line 15-15 of Fig. 14;

Fig. 16 is an enlarged section taken substantially on line 16-16 of Fig. 14;

Fig. 17 is a detail section taken substantially on line 17-17 of Fig. 16;

Fig. 18 is a vertical transverse section through the glass plate supporting means and rotary driving assembly therefor;

Fig. 19 is a top view of the glass plate supporting means;

Fig. 20 is a horizontal section taken substantially on line 20-20 of Fig. 18;

Fig. 21 is a perspective view of the template cams and the mounting therefor;

Fig. 22 is a diagrammatic illustration of the electrical system for the grinding machine; and

Fig. 23 is a detail view showing two different forms of edge grinding wheels.

Referring now to the drawings, there is illustrated a grinding machine, generally designated by the letter A and which, as pointed out above, is primarily designed for edging and/or beveling glass blanks to exact, predetermined dimensions as established by suitable template or pattern forms, although it is not restricted to such use. This machine is capable of edging glass blanks in the form of plates having a variety of dimensional sizes and of differing contours, such as substantially square, rectangular, circular, elliptical and/or combinations thereof.

It is customary in the fabrication of automobile rear view and vanity mirrors, as well as in similar and other conventional type mirrors, to mount the silvered or other coated glass plate in a metal frame or casing which is prestamped to the desired shape and size and subsequently assembled with the mirrored glass plate. Because of this, it is essential that the glass plate, to which the mirrored coating is to be applied, conform to the exact shape and size of the metal frame or casing and have suitably finished edge surfaces. With the grinding machine of this invention, it is possible to produce both the edge outline and, if desired, a bevel along one corner of the glass plate simultaneously, the edge outline being exactly ground to reproduce the outline or form of a master template or pattern in duplication of other and like glass plates. The desired angle of bevel or chamfer may be modified according to demands of the finished article by merely changing the angle of the grinding element. Thus, the glass plate B, shown in Fig. 5 as representative of the many combinations of dimensions and contours, is, in this particular instance, rectangular and has a vertically disposed edge surface C, ground to the dimension of a corresponding template, and a beveled upper surface indicated at D.

Referring particularly to Fig. 1, the grinding machine A embodies a pair of self-contained grinding units, generally indicated at E and F, said units being operatively associated with driving and/or control elements contained within the main framework of the machine. In ac-

cordance with the invention, the unit E is provided with a grinding wheel G adapted to finish grind or edge the periphery of a glass blank as indicated at C in Fig. 5, while the other unit F has a grinding wheel H dressed to simultaneously produce the bevel or chamfer D at the upper corner of the blank.

The grinding units E and F are mounted at opposite sides of a rotatable work supporting carriage I upon which the glass blank J to be ground is carried. The grinding units are mechanically interconnected so that they move in unison through one operating cycle while the glass supporting carriage I is rotated through substantially one and a half revolutions. Movement of the grinding units toward the glass blank and the subsequent return to their idle positions, is accomplished within a portion of a half revolution of the glass supporting carriage I, thereby assuring completion of the grinding cycle with a continuance of grinding, or overlap, along and beyond the initial area of engagement of the grinding wheels G and H and the glass blank J to eliminate any possibility of incomplete edging. During the inward movement of the grinding units E and F, the glass blank J is revolved from its position of loading until engagement of the grinding wheels therewith has been effected and further approaching movement of said grinding units is monitored by the control elements of the grinding machine.

Broadly speaking, the cyclic operation of the grinding machine is semi-automatic; operation of the grinding units E and F being initiated when the glass blank J has been loaded upon the supporting carriage I and subsequently being halted automatically upon the completion of the grinding cycle. As will be more fully hereinafter set forth in detail, the glass blank J is firmly held upon the supporting carriage I by vacuum and is removable therefrom when such vacuum is destroyed. This is accomplished by the operator who actuates suitable controls generally indicated at K, for the vacuum and machine system, and upon the release of which the vacuum condition will be reestablished and operation of the machine initiated.

With reference now more specifically to the constructional details of the grinding machine A, it will be noted throughout the several assembly views that the supporting frame 20 of the machine comprises an upper, rectangular, tray-like platform 21 arranged above the base 22 and supported by pairs of corner pillars 23 and 24. The pillars 23 are disposed in the corners at one end of the base 22 while the pillars 24 are disposed in the opposite end corners. The pillars 24 are somewhat shorter than pillars 23 due to the provision of a reservoir 25 within the base 22 for storage of liquid coolant. Located substantially midway between the platform 21 and base 22, is a horizontal shelf 26 supported at one end on legs 27 and at the opposite end by an angle brace 28 secured to the corner pillars 24. Suitable closure panels 29 may be secured to the pillars 23 and 24 to enclose the sides and ends of the framework 20 and, if desired, a splash guard 30 may be carried by the platform 21 as shown in Figs. 1 and 3, said guard being supported by clips 31 that engage the upper edges 70 of the side wall 32 of the platform, the bottom of which is designated 33.

The bottom 33 of the platform 21 is provided with aligned openings 34, 35 and 36 (Figs. 7 and 14) which are formed to receive the carriages 75

of the grinding units E and F and the spindle assembly, generally designated at 37, for rotation of the supporting carriage I. The openings 34 and 36 are covered by slide housings 38 having elongated passageways 39 formed therein and bounded by the vertically rising walls 40 through which the body portions of the carriages 41 and 42, for the grinding units E and F respectively, extend and move in their reciprocal travel. The carriages 41 and 42 are composed of identically component parts, usually termed "right" or "left" hand as the case may be. For brevity of description, only the right hand carriage 42, shown in detail in Figs. 14 and 16, will be described but it will be understood that the description of said carriage applies equally as well to the opposite or left hand carriage 41.

As illustrated in Figs. 14 and 16, the carriage 42 is composed of a base member 43 and a vertically disposed riser member 44 which extends through the passageway 39 and on which the motorized grinding unit F is mounted. The base member 43 and riser member 44 are secured together by machine screws or the like 44' and the said base member is supported for longitudinal movement between the depending wall portions 45 of the housing 38 by means of ball bearing assemblies 46 (Fig. 16). These bearing assemblies comprise a pair of rail sections 47 and 48 and a series of balls 49. More particularly, the rail section 47 of each bearing assembly 46 is secured to the depending wall 45 of housing 38, while the component rail section 48 is secured to the side wall of the base member 43. The inner opposed surfaces of these rail sections have V-shaped grooves 50 formed therein in which the balls 49 are located. The balls are confined by a cage or suitably apertured plate 51, and to prevent escape of the balls from either end of the rail sections, retainer plates 52 are affixed to the ends of the rail sections 48 as shown in Fig. 3, to engage one end or the other of the plates 51.

The riser member 44, which is carried by and movable as a unit with the base member 43, has an upwardly extending wall 53 received within the passageway 39 of the related slide housing 38. The wall 53 is reenforced by vertical transverse flanges 54 and is provided with a horizontally disposed top 55 having a peripheral flange or skirt portion 56 which projects downwardly over the upper portion of the wall 40 of housing 38. The peripheral flange 56 coacts with the rising wall 40 of housing 38 to enclose the passageway 39 and prevent entrance and drainage of escaping coolant as it is thrown by the grinding wheels G and H. As shown in Fig. 14, the top 55 is of sufficient length to permit adequate longitudinal movement of the carriage 42 relative to the housing 38. Thus, the carriage 42, and similarly the carriage 41, is adapted to move within the respective housing 38 with a minimum of friction into and out of operative position with respect to the glass blank J and to also move in response to the shape of the work piece during the grinding cycle to suitably edge and/or bevel the same.

The riser member 44 of the carriage is, as shown in Figs. 14 and 16, provided with a horizontally undercut guideway 58 in which is mounted a supporting member 59 for the motorized grinding spindle assembly 60 (on the right hand) of the grinding unit F. The supporting member 59 is formed of separable though rigidly interconnected members, namely, a slide member 61

and a bracket member 62. The slide member 61 has beveled upper and lower edges 63 and 64, respectively, received in the guideway 58, and a laterally disposed flange 65 to which the bracket member 62 is connected by bolts or the like 66 and 67. The beveled upper and lower edges 63 and 64 of the slide member 61 engage the corresponding undercut surfaces 68 and 69 of guideway 58, and the undercut surface 69 is preferably formed on a gib plate 70 which is located in and secured to the guideway 58 when the parts are assembled.

The bracket member 62 has a corresponding flange plate 71 which is axially drilled, as at 72, to receive a horizontal shaft 73 which is carried in the flange 65 (Fig. 17) and is rigidly secured therein by a set screw 74. Since the shaft 73 is loosely received within the opening 72 in flange plate 71, the said flange plate may be shifted angularly with respect to the said flange 65 to effect the desired angular adjustment of the grinding unit relative to the work. To secure the flange plates 65 and 71 in rigid relation and yet permit such angular movements as become necessary, the said flange plates are provided with arcuate slots 75 and 76, respectively, the bolts 66 and 67 extending loosely therethrough and threaded into the opposed flange plates. Carried by the bracket member 62 is a vertically disposed clamping collar 78 which receives the annular portion 79 of the grinding spindle assembly 60 and which is secured therein by screws 80. The position of the bracket member 62 with reference to the slide member 61 may thus be corrected to maintain the grinding unit in vertical position by shifting the member 62 angularly to the member 61 upon loosening the bolts 66 and 67 and swinging the bracket member 62 upon the shaft 73 with reference to the slide member 61.

The member 61 is slidable within the guideway 58 to move the motorized grinding spindle assembly 60 toward and away from the work holder I. For this purpose, there is provided a block 81 secured to the slide member 61 and extending through a rectangular aperture 82 formed in the vertical wall portion 83 of the guideway 58. The block 81 is drilled and tapped as at 84 to receive a regulating and adjusting screw 85 which is turnable by a handle 86. The screw 85 has a shank portion 87 journaled in ribs 88 extended from the wall 83. To prevent endwise movement of the screw 85, there is provided a collar 89 which is secured to the shank portion 87 between the ribs 88. Upon rotation of the screw 85, the block 81 will be moved along its threaded portion and consequently the slide member 61 will be adjusted to any required position by longitudinal movement in the guideway 58.

Provision is made for locking the screw 85 against rotation to secure the parts in predetermined fixed position by means of a clamping shaft 90 located in the block 81 at right angles to the screw 85. The shaft 90 has a threaded end 91 and a handle 92 secured at its opposite end. The threaded end 91 is received in a tapped hole 93 formed in the block 81 and slide member 61. To effect a clamping relation between the block 81 and screw 85, the block 81 is slotted to provide jaw portions 94 in alignment with and extending through the tapped hole 84 so that upon rotation of the shaft 90, the handle 92 will be urged against the outer surface of the 75

block with sufficient thrust to compress the jaws 94 and thereby firmly grip the screw 85.

By releasing the handle 92 and turning the handle 86 of adjusting screw 85, the slide member 61 of either grinding unit E and/or F can be moved within the guideway 58 and the grinding spindle assembly 60, carried in bracket member 62, will be extended or retracted so that the grinding wheel G and/or H mounted thereon can be initially located with reference to the work supporting carriage I. Each of the grinding units E and F is thus provided with adjusting and/or compensating means for positioning of their respective grinding spindle assemblies 60 to the end that said assemblies will be properly disposed with reference to the glass carriage I and also be suitably supported in a vertical plane.

The spindle assembly 37 of the work supporting carriage I is interposed between the grinding units E and F so that the glass or other work blank J, which is carried on said supporting carriage I, will be ground along its edge portions as the grinding units are urged thereagainst, as will be more fully hereinafter described. The spindle assembly 37 is composed of two aligned shafts 95 and 96 that are keyed together at their adjoining ends and supported to rotate as a unit. As shown in Fig. 18, the shaft 95 is journaled in spaced bearings 97 supported in the opposite ends of a casing 98 mounted on the shelf 26 and enclosed by cap plates 99. The shaft 96 is arranged above shaft 95 and has annular shoulders 103 formed in its surface for receiving the inner cones of roller bearings 101. The outer races of the bearings 101 are contained in fitting end portions 101' of a housing 102. The housing 102 constitutes a centrally disposed part of a cover plate 103 which has an annular rim 104 fitting within the opening 35 in the floor 33 of platform 21.

The shafts 95 and 96 are connected together at their inner ends by a plate assembly shown in Figs. 18 and 21, and which comprises end plates 105 and 106 and intermediate cam plates 107 and 108 which constitute one cam control assembly 45 for governing the movements of the grinding units E and F.

The end plate 105 is secured by screws 109 to the end of the shaft 96 and is provided with a centering plug 110 received in a recess or socket 111 in said shaft. The plate 105 also has a depending axial sleeve portion 112 on which the cam plates 107 and 108 and the end plate 106 are centrally aligned. The sleeve 112 extends beyond the end plate 106 and is received within the socket 113 in the shaft 95. The openings in the plug 110 and sleeve portion 112 align with and form continuations of the axially formed bores 114 in the shafts 95 and 96 to extend from one end to the other of the spindle assembly 37.

The end plate 105 is drilled to receive screws 115 which extend through the template cam plates 107 and 108 and are threaded into the end plate 106. The cam plates 107 and 108 are located so that they can be employed as a control template for two differing forms of glass blank to be ground and whereby a change-over can be quickly effected without too much "downtime" of the machine. The template cam plates 107 and 108 are initially secured together, previous to being secured with the plates 105 and 106, by means of screws 116. The template cam plates 107 and 108 are shown as being of the same width but differing in length. However, template cams of different shapes and/or sizes can be substituted

70

for the templates 107 and 108, depending upon the size and/or shape of work to be edged.

The end plate 106 is centrally formed to receive the adjacent end of shaft 95 and is preferably slotted as at 117 in which are secured keys 118 held in place by set screws 119. The periphery of the shaft 95 is provided with complementary keyways 120 for receiving the keys 118 to thereby interconnect the shafts 95 and 96 so that they rotate as a unit.

The shaft 95, journaled in bearings 97 in gear case 98, is extended through the lower capping plate 99 to afford a connection to a stationary gland 121. This gland is connected by a pipe 122 with a conventional vacuum system, generally indicated at 123 in Fig. 1 and which includes a tank 124, pump 125 and motor 126. The pipe 122 is, more particularly, connected to an electrically actuated control valve 127 that is connected to the tank 124 by a pipe 128 and thus controls communication between the pipes 128 and 122 and to the gland 121. Said gland is, as shown in Fig. 18, provided in its ends with suitable packing elements 129 and with the gland intake port 130. The outer surface of the shaft 95 is provided with an annular groove 131 in registration with the port 130 of the gland, said groove communicating with the axial passageway 114 through a plurality of openings 132. When the control valve 127 is open, the vacuum established in tank 124 will create a reduction in pressure in pipes 128 and 122, gland 121 and passageway 114 of the spindle assembly 37, which reduction in pressure extends to the work supporting assembly I to maintain the work in position thereon during grinding, as will be more fully hereinafter described. The lower end of the shaft is closed by a plug 133 and is externally threaded to receive a nut 134 which supports a bearing washer 135 for the gland 121. The gland 121 is secured against rotation by means of a bifurcated bracket 136 which is secured to and depends from the shelf 23.

The upper end portion 137 of shaft 96 is reduced in diameter to receive an annular splash guard 138 supported on the shoulder 139. This splash guard is secured in position against said shoulder by a sleeve 140 pressed onto the end 137 of the shaft.

The work supporting assembly or holder I comprises a work block 141 for supporting the glass blank J, a vertically movable plate 142 and a channeled collar 143 carrying said plate, the work block 141 having a centrally formed recess 144 in the bottom surface thereof in which the upper end of shaft 96 is received. The work block is fixed to the shaft by screws 145 which are located in said block (Fig. 19) and threaded into the end of the shaft.

The work block 141 is provided in its upper surface with recesses 146, and has suitably secured to its upper surface a layer 147 of soft material, such as Ebonite or the like, having openings 148 in registration with the recesses 146. Each recess 146 communicates with a central bore 149, drilled longitudinally through the work block, by means of transverse passageways 150. The bore 149 is closed at both ends by plugs 151 and, by means of a centrally disposed hole 152, is connected with the passageway 114 extending axially through the shafts 95 and 96 and in communication with the gland 121 at the lower end of shaft 95. By connection of the said gland to the evacuating system 123, as has been explained, the glass blank J will be firmly held upon the work block 141 during the grinding operation.

As shown in Fig. 18, the vertically movable plate 142 and supporting collar 143 are disposed beneath the work block 141 and are so interrelated as to move as a unit. The channeled collar 143 has a shoulder 153 formed in its upper surface against which the plate 142 is received, said plate being secured thereon by screws 154, as shown in Fig. 20. The collar may thus be actuated to move the plate 142 vertically toward and away from the work block 141. To afford a bearing surface for reciprocal movement of the parts, the collar has a sleeve 155 contained therein which is slidably mounted on the sleeve 140 on shaft 96.

The plate 142 is movable relative to block 141 to locate vertically disposed work retaining fingers 156 either above or below the upper surface thereof. The fingers 156 have tapered upper end surfaces 157 which receive the rough glass blank J during its initial placement on the work block 141, said fingers being movable in openings provided by notches 158 (Fig. 4) formed in the sides and ends of the block 141 and plates 159 which close the same. The lowermost ends of the fingers 156 are notched, as at 160, to enter corresponding notches 161 in the plate 142 so as to be slidable therein according to the dimensional size of the block and so that the said fingers can be adjusted to move freely within the openings afforded by the notches 158. The glass blank J is thus initially located, with reference to the surface of the block by means of the fingers 156, and subsequently lowered onto the surface layer 147 as the collar and plate are moved downwardly beneath the block and along the sleeve 140.

Within the channel 162 of collar 143, is a split ring 163, the halves of which are secured together in a conventional manner by screws 164. The assembled ring 163 is connected by means of diametrically extending pins 165 to an actuating lever 166 intermediate the ends thereof. The association between the collar 143 and ring 163 is such as to effect movement of the collar in a vertical direction while preventing rotary movement of the ring with the collar. The lever 166 comprises two parallel bars 167 disposed at opposite sides of the ring 163 and pivotally supported at its rear end by a transverse rod 168 mounted at its ends in a bracket 169 secured on the wall 32 of the platform 21 (Fig. 18). The forward ends of the bars 167 are interconnected by a transverse rod 170 in order that said bars will move as a unit. Each of the bars is provided with a slot 171 (Fig. 20) in which is located a slide block 172 drilled to receive the pins 165 of the ring 163. Thus, as the lever 166 is swung vertically upon rod 168, the positional relation of said lever and pins 165 will be compensated for by sliding movement of the blocks 172 in their respective slots 171.

Upon movement of the forward end of the lever 166 in an upward direction, the ring 163 raises the collar 143, and with it the plate 142 carrying the locator fingers 156. Preferably, the extent of this movement is sufficient to project the tapered ends 157 of said fingers above the elevation of the block 141 for convenient placing or removal of the glass blanks or finished plates; while in their lowermost position, the tapered ends 157 of the fingers 156 are well below said top elevation of the block.

The lever 166 is actuated during the manually controlled phase of the machine cycle or while a finished plate, such as that indicated at B in

Fig. 5, is removed from the support assembly I and is subsequently replaced by a rough blank J, as best seen in Fig. 4. When making this substitution, the operator raises the lever 166 and simultaneously places a temporary control on the operative system of the machine by means of a hand lever 173 or an interconnected foot treadle 174. As shown in Fig. 1, the lever 173 and treadle 174, which constitute the manually operable control means K, are interconnected by means of a link 175. The hand lever 173 is fixed to a shaft 176 which is rotatably mounted in the front wall 32 of the platform 21 intermediate its ends. Fixed to the inner end of shaft 176 is a transverse crank arm 177 which carries at its outer end a crank pin 179 projecting toward and beneath the rod 170 of lever 166 so as to lift the forward end of the lever 166 when the hand lever 173 is swung in a clockwise direction (Fig. 7). This movement, being transmitted to the collar 143 through the lever 166 and pins 165 of ring 163, causes the plate 142 and fingers 156 carried thereby to raise the glass blank or plate from the work block 141 to an elevated position for removal. The treadle 174 is carried by a shaft 178 secured in the wall of the base 22 and in general vertical alignment with the hand lever 173.

While either the hand lever 173 or treadle 174 is swung clockwise, and before the fingers 156 engage the glass blank or plate, a horizontal arm 180 extended from the link 175 contacts and opens a switch 181 which is mounted on one of the legs 27 of the shelf 26. The switch 181 forms a part of the control circuit for the evacuating system 123. More particularly, the switch 181 controls the electrically actuated valve 127 (Figs. 1 and 22) which is positioned between the pipes 122 and 128 from the tank 124 to the gland 121. As previously set forth, the said gland encircles the end of shaft 95 of spindle assembly 37 and consequently when the valve 127 is closed by actuation of switch 181, the vacuous condition created in the pipes 122 and 128, passageway 114 and block 141 of the work holder, is destroyed, whereupon the glass blank or plate may be removed. On the other hand, when the hand lever 173, or treadle 174, is released, the arm 180 will be moved away from the switch 181 and the valve 127 opened to reestablish the vacuous condition, and the vacuum created within the recesses 146 of work block 141 will draw and hold the newly placed rough blank J securely against the surface layer 147 of the work holder.

Reversal of movement of the manually actuated hand lever 173 or treadle 174, will release the switch 181 from the control of the arm 180 and also permits the bar 177 to lower the lever 166 whereby the plate 142 and collar 143 will withdraw the tapered ends of the fingers 156 from above the block 141 and allow the glass plate to settle into position on the upper surface thereof. To insure automatic return of the manually actuated members 173 and 174 to inoperative position upon the release thereof by the operator, a spring 182 is connected between the arm 180 and base 22 of the machine to reverse the movement of the hand lever and treadle (counterclockwise) when they are released.

Provision is made for automatically starting the grinding cycle of the machine when the hand lever 173, or treadle 174, is released after the finished plate has been removed from the work holder and a rough blank secured by vac-

uum thereto. In Fig. 2, the hand lever 173 is illustrated by full lines when in inoperative position and by the broken lines when moved to operative position. The lever has formed thereon 5 a bifurcated extension 183 between the side portions of which is received a dog 184 eccentrically supported on a pintle 185 and having a flattened end 186 normally abutting the wall 187 of the extension 183. When the hand lever 173 is 10 located in full line position, the outer end 188 of dog 184 is positioned above the adjacent end of a trip bar 189 carried on a pivot pin 190 secured to the wall 32 of platform 21. During turning of the lever 173 clockwise to the position indicated 15 in broken lines, the dog 184 will strike the end of the trip bar 189 and the said dog will swing upwardly about the pintle 185, until it passes beneath the trip bar 189.

However, when the hand lever 173 is released 20 so as to return to its original position, the end 186 of the dog, in its abutting relation with reference to the wall 187, resists movement of said dog and as the opposite end 188 engages the trip bar 189, rotation of said trip bar upon pivot pin 190 will be effected. Upon such rotation, the opposite end of the trip bar will be moved into contact with the plunger 191 of a limit switch 191. The switch 191 is included in the control circuit of the drive motor 192 for the machine. 25 Thus, when the dog 184 is moved upwardly, the trip bar 189 will be rotated to actuate the limit switch 191; and, as the dog disengages the bar, the said bar, under the influence of a spring 193, will return to its normal position and the cyclic 30 operation of the machine will have been initiated.

During each operating cycle of the machine, the carriages 41 and 42 of the grinding units E and F respectively are caused to move longitudinally inwardly toward the work supporting 35 assembly I and work J mounted thereon by the rotation of a cam 194 (Fig. 8), said cam also subsequently effecting the outward movement of the grinding units to return them to their starting positions. When the grinding units 40 reach the limit of their inward movement, they are brought into operative engagement with the template 107 carried by spindle assembly 37 and 45 remain in engagement with said template during the grinding cycle.

The cam 194 and spindle assembly 37 are 50 driven through an interrelated mechanism from a drive motor 192, with a differential gearing being interposed so that the template 107 will be caused to rotate one and one-half revolutions while the cam 194 rotates one complete revolution. The rotation of the template 107 will of 55 course be imparted to the work block 141 and work blank J, the reason for rotating the work blank one-half revolution more than the cam 194 being to effect an overlapping of the grinding 60 cycle at the completion of the grinding cycle.

It has been found from actual experience that 65 if the work block or holder 141 is located diagonally, as illustrated in Figs. 4 and 7, instead of in alignment with either the longitudinal or transverse axis of the machine, the glass or other work blank J can be more easily placed thereon and removed therefrom since it results in a more physically natural movement of the operator's 70 hand during loading and unloading. Therefore, at both the beginning and end of the machine cycle, the work holder is preferably disposed diagonally as in Figs. 4 and 7.

In order to illustrate somewhat more in detail

the relative differential of rotation established and maintained between the grinding units E and F on the one hand and the work supporting carriage I on the other, or more particularly between the cam 194 and template 107, there is indicated in Fig. 6 a series of radially changing arrows *a* and *b* representing respectively the glass blank J and cam 194. The succeeding positions assumed by the glass blank and cam during one complete machine cycle are diagrammatically shown at *c* to *k* inclusive.

The letter *c* designates the relative positions of the glass blank and cam at the start of the machine cycle, while the letter *k* designates their relative positions at the completion of the grinding cycle. It will be seen that between positions *c* and *k*, the glass blank J rotates one and one-half revolutions while the cam 194 completes one revolution. Upon placing of the machine in operation, the glass blank J will be revolved clockwise approximately 45 degrees, while the cam 194 is being rotated only approximately 30 degrees to the positions indicated at *d*. During this time the grinding units will be moved inwardly into engagement with the template 107 and the grinding wheels G and H into contact with the glass blank J. Upon continued rotation of the work holder and cam and during movement thereof from positions *d* to positions *h*, the edges of the glass blank will be subjected to the action of the grinding wheels and will complete one full revolution while the cam 194 turns through substantially two-thirds of a revolution. As the work holder rotates from position *h* to position *j*, it moves into its second revolution while the cam has substantially completed its first revolution. During this period, the grinding operation will continue approximately 45 degrees beyond the initial point of contact of the grinding wheels with the glass blank to assure that the entire edge of the glass blank has been properly ground. Upon movement of the work holder and cam from position *j* to position *k*, the grinding wheels will be moved outwardly away from the work and back to starting and rest positions.

As shown in Fig. 1, the drive motor 192 is mounted on the base 22 and drives a hydraulic transmission unit 195 through belts 196 trained about the respective pulleys of the motor 192 and transmission unit 195. The output shaft of the unit 195 is coupled to a pair of worm drives, generally designated 197 and 198 (Fig. 14), which drive the work spindle assembly 37 and cam 194 respectively. While it is preferred that the worm drives 197 and 198 are designed to produce clockwise rotation of their respective driven members, it is possible, and may at times be found advantageous, to cause said worm drives to effect rotation of the work spindle assembly 37 and cam 194 in a counter-clockwise direction.

The horizontally aligned shafts 199 and 200 of worm drives 197 and 198 preferably are operated from the output shaft of the transmission 195 by means of a chain drive comprising the sprockets 201 and 202 and the chain belt 203, which passes through a cored opening 204 provided in the shelf 26. The sprocket 201 is associated with the transmission 195 while sprocket 202 is carried by couplings 205 keyed to the extended and opposed ends of the shafts 199 and 200. These shafts are provided with worms 206 and 207 respectively, the shaft 199 and worm 206 being journaled within the gear case 93 mounted on shelf 26, while the shaft 200 and

worm 207 are journaled in a similar gear case 208. Preferably, the worm drives 197 and 198 have a speed ratio of 60-40.

The worm 206 carried by shaft 199 is supported within the case 93 in meshing relation with a worm gear 209 (Fig. 18) mounted on the shaft portion 95 of the spindle assembly 37 and secured thereto by a spline key 210. Rotation of the spindle assembly and work holder is thus effected by the drive motor 192 and will be of the desired speed according to the gear ratio as to rotate the work supporting carriage I approximately 45 degrees before engagement of the grinding wheels G and H with the edges of the work blank J as explained above in the description of Fig. 6.

The worm 207 is in meshing relation with a worm gear 211 carried on a vertically disposed shaft 212 journaled in the gear case 208 (Fig. 8) and having keyed to the upper end thereof the cam 194. Mounted for rolling engagement with the edge of cam 194 is a roller 213, rotatably carried by a shouldered stud 214 in a suspended arrangement on a lever arm 215 (Fig. 14), to reciprocally swing said lever arm during one complete rotation of said cam. The lever arm 215 is journaled at its rear end on the upper end of a vertical post 216 (Fig. 10) mounted on the shelf 26 and having a shouldered portion 217 on which the lever is supported, and a threaded end 218 for receiving a retainer nut 219. Said lever arm 215 is normally urged inwardly to maintain the roller 213 in engagement with cam 194 by means of an articulated linkage, generally indicated at 220. In the construction shown, this linkage 220 comprises a horizontal slide bar 221 with which the forward end of lever arm 215 is slidably associated, and a link belt 222 connected at one end to a plate 223 carried by slide bar 221 and at its opposite end to a weight 224 through a cable 225.

The forward swinging end 226 of lever arm 215 is slidably supported in a block 227 having a pin extension 228 which is located in a socket 229 formed in the slide bar 221 intermediate the ends thereof and by which it is pivotally associated therewith (Fig. 12). Said slide bar is supported at its opposite ends in brackets 230, secured to the shelf 26, and is slidable therethrough upon rotation of the cam 194.

The link belt 222 is trained intermediate its ends about gears 231 and 232. The gear 231 is mounted on a flanged collar 233 journaled by the needle bearing 234 and supported on the annular shoulder 234' of the shaft portion 95 which constitutes the lower portion of the spindle assembly 37 (Fig. 18). Also carried by the collar 233 is a cam 235 which rotates as a unit with the gear 231. The idler gear 232 is rotatably supported on a shoulder 236 on post 216 beneath shoulder 217 which supports the lever 215 (Fig. 10). The weight 224 is located within one of the pillars 24 of the machine as shown in Figs. 3 and 8, and the cable 225 carrying said weight passes over a sheave 237 rotatably mounted on a horizontal shaft 238 journaled in the walls of the pillar.

The cam 194 comprises a substantially flat plate of irregular outline having a high or peak area 239 (Fig. 6A) and a diametrically opposed low or dwell area 239a. Interconnecting these areas is a descending cam surface portion 239b and a subsequent rising portion 239c. Thus, as the cam rotates in a clockwise direction from the full line position in Fig. 6A, the follower roller

239 along the descending cam surface 239b to the dwell area 239a; this action being similar in radial motion to that of the arrow b (Fig. 6) from position c to position e. Upon continued rotation of the cam, the roller 213 will leave the dwell area 239a and follow along the rising cam surface 239c to the peak area 239 which completes one revolution of the cam and corresponds to position k in Fig. 6.

In rolling engagement with the peripheral edges of the cam 235 are two rollers 240 and 241 depending from the forward ends of bars 242 and 243 and journaled on respective shafts 244 and 245 (Fig. 11) that are secured in the said bars. The bars 242 and 243 have integral tubular mounting sleeves 246 at the rear ends thereof of which are rotatably supported on vertical posts 247 mounted on the shelf 26 (Fig. 18).

The free forward ends of the bars 242 and 243 are pivotally connected by pins 248 and 249 to the adjacent ends of links 250 and 251 respectively, which are carried at their opposite ends by the base members 43 of the carriages 41 and 42 (Fig. 14). As herein shown, each link 250 and 251 has a plurality of holes 252 formed therein in adjacent the end thereof and a pin 253 is passed through one of the holes according to adjustments which may be found advisable when setting up the machine. The pin 253, in each instance, is secured by a set screw 254 in a plug 255 having a threaded end 256 by which said plug is connected to the base member 43. The links 250 and 251 are free to swing about the axis of their respective pins 253 in complementary radial movement to the bars 242 or 243 as said bars are actuated by oscillation of the cam 235.

Through the interrelation of the bars 242 and 243, the links 250 and 251 and the carriages 41 and 42, the rollers 240 and 241 are normally urged into engagement with the cam 235. This is accomplished and the weight of the carriages 41 and 42 counterbalanced by means of cables 257 and 258 secured at one end by studs 259 and 260 to the respective bases 43 of said carriages and having connected to their opposite ends the weights 261 and 262. The respective weights for the carriages are located, as the weight 224, in the supporting pillars of the framework 20. Thus, the weight 261 for the carriage 41 is located in the pillar 24, in the opposite corner from that pillar 24 in which the weight 224 is located and the cable 257 thereto is trained over a sheave 263 supported on a shaft 264 journaled in the walls of the pillar. In a corresponding manner, the weight 262 for the carriage 42 is located in one of the pillars 23 and the cable 258 therefor is trained about a similar sheave 265 supported on a shaft 266.

The cam 235 is driven from the cam 194 through the linkage 220 first in one direction and then the other to effect the inward and outward travel of the grinding units E and F at the beginning and end respectively of each machine cycle. The relative positions of the cams 194 and 235 at the beginning of the machine cycle are shown in Fig. 8 and during the grinding operation in Fig. 9. These relative positions of the two cams are also illustrated diagrammatically in full and broken lines in Fig. 6A.

The cam 235 comprises a substantially flat plate including a central body portion 267 provided with diametrically extending wing portions 268a and 268b having oppositely facing cam edges

268c for engagement by the rollers 240 and 241. Upon rotation of the cam 194 in a clockwise direction from its full line position in Fig. 6A to its broken line position, the cam 235 will likewise be rotated in a clockwise direction from its full line position to its broken line position by the linkage means 220. Simultaneously, the follower rollers 240 and 241 will move inwardly along the cam edges 268c, and the weights 261 and 262, acting through cables 257 and 258 to the carriages 41 and 42, and their respective links 250 and 251, will effect movement of the carriages 41 and 42 toward each other and the grinding wheels G and H into grinding engagement with the work piece J. During the inward movement of the carriages 41 and 42, the spindle assembly 37 and work piece J will rotate from position c in Fig. 6 to position d.

Carried by the carriages 41 and 42 are annular follower plates 269 and 270 adapted to engage the peripheral edges of the template 107 when the grinding units are moved inwardly to grinding position. These annular follower plates 269 and 270 are of a predetermined diameter according to the diameter of the grinding wheels G and H, so that they will engage the template 107 and thus limit the inward movement of the grinding units before the rollers 240 and 241 complete their inward travel along the cam edges 268c. Thus, the follower plates 269 and 270 act to hold the rollers 240 and 241 from engagement with the cam 235 so that during the grinding cycle, the inward and outward movements of the grinding units will be controlled by the cooperating action of the template 107 and follower plates 269 and 270 without interference by the rollers 240 and 241 which are maintained in a floating position. Consequently, during the actual grinding cycle, as indicated between positions e and j (Fig. 6) reciprocal movement of the grinding units will be produced by rolling engagement of the followers 269 and 270 along the peripheral edge of the template 107 and independent of the initial and subsequent control of the cams 194 and 235.

When the cam 194 has rotated so as to enter the remaining sixth of its rotation, the roller 213 will follow the rising cam surface portion 239c thereof and, through the lever 215 and linkage 220, produce a counter-clockwise rotation of the cam 235. The cam edge surfaces 268c of the wing portions 268a and 268b will now pick up, in rolling engagement, the rollers 240 and 241, whereupon the bars 242 and 243 of each related carriage, will be swung outwardly to remove the followers 269 and 270 from engagement with the template 107. This constitutes completion of the grinding cycle, but the machine cycle is not complete until the cam 194 completes a full revolution and returns to its starting full line position in Fig. 6A, at which time the grinding units have been moved outwardly to their starting position.

The follower plates 269 and 270 (Figs. 14 and 15) are rotatably supported on similar, vertically disposed shafts 271 journaled in the outer ends of horizontal brackets 272. The brackets 272 are secured at their inner ends to the flanged outer ends 273 of bars 214. The flanges 273 are slotted as at 275 to receive fastening bolts 276 which are threaded into the adjoining face of each bracket 272 (Fig. 15).

The bars 274 are carried on the base 43 of the respective grinding unit E or F by means of a washer 277 and a nut 278 associated with a threaded stud 279 which is secured in the base of

the respective carriage 41 or 42. As shown in Fig. 13, each bar 274 is supported at its outer end by a cross plate 280 affixed to depending lugs 281 from the base 43. The opposite sides of the bar are engaged by set screws 282 threaded through lugs 281 and held from rotation by lock nuts 283. By adjusting the set screws 282, the bar 274 may be located in or at an angle to the longitudinal axis of the machine. Each bracket 272 carries a horizontal stub shaft 284 received in a socket 285 in the respective bar 274, in parallel alignment to its longitudinal axis but eccentrically with respect to its horizontal axis as shown in Fig. 15. By loosening the bolts 276, the bracket 272 of the related follower plate 269 or 270 can be shifted angularly until the plate is brought into a substantially horizontal plane so as to travel evenly along the peripheral edge of the template 107.

When setting up the machine for any particular shape of template 107, the grinding units are usually moved inwardly until the follower plates 269 and 270 contact the edges of the template 107, while the same is stationary, so that the peripheral grinding surfaces of the grinding wheels G and H will be satisfactorily disposed in contact with the edges of a test work piece of the desired predetermined size. Any necessary adjustments may then be effected by loosening the clamping shaft 90 to free the adjusting screw 85 from the jaws 94 and turning screw 85 by its handle 86 to move the slide member 61 along and within the guideway 58. The grinding units E and F may thus be individually located to obtain the most effective edging and/or beveling of the glass plate, after which the shaft 90 is again turned to replace the jaws 94 in clamping relation about the screw 85.

Upon completion of the machine cycle, as determined by one revolution of the cam 194, the lever 215 will be swung to urge the slide bar 221 rearwardly in brackets 230. The bar carries on its under surface a block 286 having a sloping area 287 adapted to engage the plunger 288 of a limit switch 289. The limit switch 289 is secured on the shelf 26 and, when actuated, interrupts a control circuit for the power circuits to the drive motor 192 and consequently when the bar 221 moves to the position shown in Fig. 1, the switch 289 is opened and operation of the machine ceases.

A coolant system, generally designated 290 in Fig. 1, is provided for supplying the usual liquid to the grinding wheels G and H and thence to the work piece J. This system comprises a pump 291 driven by a motor 292. A pipe 293 runs from the reservoir 25 in base 22 to the pump 291, and a distributor pipe 294 is extended upwardly from the pump through the bottom 33 of the platform 21 to a branch supply line 295 connecting with nozzles 296 by lengths of flexible tubing 297. If desired, the nozzles 296 may be carried by the clamping collars 18 of the support members 59 by means of clips 298. The escaping coolant is collected on the bottom 33 and, as it increases in quantity, moves toward the end areas thereof. To provide a partial filter for the coolant liquid, a pair of curbs 299 are formed integrally with the bottom, extending between the side walls 32 and arranged to divide the central floor area from end drainage areas. When the liquid overflow reaches said end areas, it is drained therefrom through suitable openings 300 to pipes 301 adapted to convey the liquid back to the reservoir 25 whence it is subsequently recirculated through usual filtering devices by the pump 291.

The electrical controls and circuits for the mechanical and vacuum systems are illustrated in the wiring diagram in Fig. 22. As therein shown, a master switch 302 is located between the positive main line 303 and the various control circuits for the main drive motor 192; the vacuum control valve 127; the motor 126 for operating the vacuum system 123 by which the work piece J is secured to the work support I; and the motor 292 for operating the coolant system 290 which supplies coolant liquid to the grinding wheels G and H and work piece J during grinding. When closed, the master switch 302 completes a circuit to the normally open limit switch 181 by lines 304 and 305 to control the operation of the vacuum system valve 127; to the coil 306 of starter relay switch 317 for the motor 126 through line 308 for operating the vacuum system 123; to the normally open limit switch 191 to control energization of the coil 309 of the starter relay switch 310 for the main drive motor 192 through lines 305, 311 and 312 through the emergency, normally closed switch 313; and to the coil 314 of the starter relay switch 315 for the motor 292 for the coolant system 290 by line 316.

A second master switch 317 connects the coils 318 and 319 of the starter relay switches 320 and 321 for the motors 322 and 323 of the grinding units E and F to the positive main line 303 by the lines 304 and 324 and branch lines 325. When master switch 317 is closed, a circuit from the positive main line 303 will be completed to the coils 318 and 319 by lines 304, 324 and 325, to energize the relay switches 320 and 321 and close their double contacts 328 and 329 respectively, and to the negative main line 330 by lines 331 and 332. Upon closure of the double contacts 328 and 329 of the relay switches 320 and 321, circuits will be created from positive main lines 333 and 334 to the double contacts 328 and 329 by lines 335 and 336 and thence to the motors 322 and 323, completing said circuits to a negative main line 337 by lines 338 and 339. Preferably, normally closed switches 326 and 327 are interposed in the branch lines 325 so that by actuating either of the starter relay switches 320 or 321, the motor 322 or 323 of the corresponding grinding unit may be independently operated for testing purposes.

In starting the grinding machine and before placing the work piece J on its work support I, the manually operable switches 302 and 317 are closed, thereby starting the motors 322 and 323 of the grinding units E and F, as above described. Simultaneously, the vacuum system 123 and the coolant system 290 are placed in operation. Thus, the switch 302 energizes the coil 306 by lines 304 and 308, completing a circuit through said coil to the negative main line 330 by lines 340 and 331 and actuating the relay switch 317 to close the double contacts 341 thereof. The double contacts 341 complete service circuits from the positive main lines 333 and 334 to the motor 126 of the vacuum system 123 through lines 342 and 343, said motor being connected to the negative main line 337 by lines 344 and 338. The circuit from the master switch 302 also energizes the coil 314 of the relay switch 315 by lines 304 and 316, completing a circuit through the coil to the negative main line 330 by line 345 and actuating the relay switch 315 to close the double contacts 346 thereof. Closing of the double contacts 346 completes circuits to the motor 292 for the coolant system 290 from the positive main lines 333 and 334 by

lines 347 and 348 and from the motor to the negative main line 337 through line 349. The pump 125 of the vacuum system is now driven to evacuate the tank 124, and the pump 291 of the coolant system is also driven to supply liquid, as previously described, to the grinding wheels G and H of their respective units E and F.

In the operation of the machine and when either placing a rough work piece upon the work holder at the beginning of the operation or removing the finished work therefrom at the completion of the operation, it is necessary that the switch 181 be held closed by the operator. To do this, the operator either grips the lever 173, usually by the right hand, or steps upon the treadle 174 to actuate the lever through the link 175. As the link is shifted in a vertical direction by either member, the arm 180 carried thereon engages and closes the switch 181.

The closing of the switch 181 closes contacts 350, thereby completing a circuit from the positive main line 303 through switch 302, line 305, contacts 350 and line 351 to the valve 127 and thence to the negative main line 330 through lines 352, 340 and 331. While the structural details of this valve are not shown, their function is well known in the art, it being understood that upon energization of its electrical components, the valve will close communication between pipes 122 and 128 of the vacuum system and reduce the vacuous condition in the gland 121. Since the switch 181 controls the valve 127 to temporarily destroy the vacuous condition in the gland 121 and work support block 141, the operator can easily remove the finished plate with his left hand and, while still engaging the lever or treadle, substitutes a rough blank which is supported on the locator fingers 156 of the work holder which have been elevated by rotation of the hand lever 173, through lever 166 which is swung upwardly by engagement of the lever bar 170 and the pin 179 carried as a part of the hand lever, as previously set forth. Upon release of the hand lever 173, it is swung counter-clockwise by the spring 182 to cause the arm 180 to move from contact with the plunger of the switch 181 to open the same. The fingers 156 then lower the glass blank J onto the surface layer 147 on the upper surface of the block 141 and the dog 184, carried by the lever 173, engages the trip bar 189 to actuate the limit switch 191. Upon momentary closure of switch 191, a circuit is created from the positive main line 303 through switch 302, lines 305 and 311, contacts 353 of the switch 191, line 312 and normally closed switch 313 to the coil 309 of the starter relay switch 310, and thence to the negative main line 330 by lines 354 and 331. Closing of the contacts 353 also completes a circuit by line 355 to the timer relay 356, through said timer and the closed contacts 357 of the emergency switch 313 by line 312 to the coil 309 of the starter relay switch 310.

The timer 356 is adjusted to maintain the circuit through the coil 309 closed until, by rotation of the cam 194 and the related radial movement of lever arm 215, the slide bar 221 has removed the block 286 from engagement with the plunger 288 of limit switch 289, allowing the contacts 359 thereof to close. The limit switch 191 and the timer 356 having opened, the closed limit switch 289 completes the circuit through lines 305, 360, 361, 358 and 312 to the coil 309 and thence through lines 354 and 331 to the negative main line 330. The coil 309, while energized, actu-

ates the armature of the starter relay switch 310 to close the double contacts 362 to complete circuits from the positive main lines 333 and 334 through lines 335 and 336 and 363 and 364 to the motor 192 and thence to the negative main line 337 by line 365. Said switch 191 thus starts the automatic machine cycle by the main drive motor 192 and, through the hydraulic transmission unit 195, the worm drives 197 and 198 rotatively drive the cam 194 and the spindle assembly 37. The cam 194, through the lever 215 and the linkage 220, causes clockwise rotation of the cam 235 to move the grinding units E and F toward one another and bring the grinding wheels G and H into engagement with the glass blank J, interposed therebetween.

More particularly, the cam 194, through roller 213 and lever 215, shifts the slide bar 221 within brackets 230, and causes clockwise rotation of the gear 231 as the link belt 222 moves in meshing relation therewith by movement of said bar and imposed draft of the weight 224. Rotation of the said gear and the cam 235 carried thereon causes the rollers 240 and 241 to follow the cam surfaces 268c of the cam 235, causing the pivotally jointed bars 242 and 243 and links 251 and 252 to swing in their coacting movements. As the rollers 240 and 241 roll inwardly along the cam surfaces 268c, the weights 261 and 262 urge the grinding units E and F toward one another until the follower plates 269 and 270 are brought into contact with the opposed edge surfaces of the template 107.

In moving into contact with the template 107, the follower plates 269 and 270 engage a moving surface since, as the cam 194 starts to revolve, the spindle assembly 37 also starts to revolve. Due to the speed differential imposed on the associated worm drives 197 and 198, and the worms 206 and 207 and gears 209 and 211 which constitute the same, rotation of the spindle assembly 37 is relatively more rapid. In fact, while the cam 194 is turning sufficiently to deliver the units E and F to the work and the follower plates 269 and 270 to the template 107, the shafts 95 and 96, constituting the assembly 37, have been rotated somewhat in advance to turn the support assembly I, the glass blank J thereon and said template 107 until the longitudinal axes of said template and glass blank coincide substantially with the longitudinal axis of the machine as previously described in connection with Fig. 6. Grinding of the blank to the desired finish continues while the cam 194 revolves through substantially five-sixths of its revolution. Thus, as the template 107 approaches completion of the first half of its second revolution, the cam 194 approaches completion of one revolution. The gearing ratio of one to one and a half, established by way of example, definitely assures overlap grinding of the blank J so that the grinding is carried well beyond the initial points of contact and separation of the wheels G and H to complete the grinding cycle is accomplished in advance of the completion of one machine cycle.

During movement of the cam 194 toward completion of one revolution, the roller 213 swings the lever 215 rearwardly, causing the slide bar 221 by the link belt 222 to revolve the gear 231 and cam 235 counter-clockwise, thereby moving the rollers 240 and 241 outwardly along the cam surfaces 268c. As the rollers 240 and 241 follow the said surfaces of the cam 235, the bars 242 and 243 are swung to urge the links 250 and 251 outwardly and to move the grinding units E and F

away from the work and consequently outwardly with respect to each other. This action removes the follower plates 269 and 270 from the template 107. Upon completion of one revolution and return of the cam 194, roller 213 and lever 215 to their respective starting positions, as shown in Fig. 8, the slide bar 221 is positioned so that the surface 287 of the block 286 engages the plunger 288 of limit switch 289 and, through the electrical circuits above described, halts 10 operation of the motor 192.

If it is found necessary to stop the machine operation during the automatic machine cycle, the emergency switch 313, located in line 312, can be manually opened by the operator, thereby breaking the circuit, through its contacts 357, to the coil 309 of starter relay 310, thus halting the motor 192.

It has been found advantageous to support the bar 274 so that it may be shifted angularly in a horizontal plane since the accuracy of grinding control is dependent upon the association between the follower plates 269 and 270 and the template 107. In setting up the machine for differing types of contour grinding, slight angular deviation of the bar's position will prevent "walking" of the follower plates 269 and 270 which will occur when the shape of the template, in turning, allows the plate to revolve along a portion of the template edges without simultaneous inward and outward movement necessary to reproduce the template outline on the work piece. Having observed the reaction of the follower plates 269 and 270 to the template 107 and particularly as said template 107 turns from its shorter to its longer dimension and back again to produce the minimum to maximum extents of travel, the bars 274 may be angularly swung on the studs 279 are locked in the desired position after adjustment by the set screws 282.

The bars 274 are also adapted to dispose the cam follower plates 269 and 270 in related positions to follow the peripheral edge of the template 108. This template, by way of example, has a longer dimension than the template 107 as may be seen in Figs. 18 and 21. An immediate change-over may therefore be accomplished so that glass blanks of adequate rough size can be finished to the dimensions of template 108 without a complete alteration of the machine. Change from the upper template 107 to the lower template 108 is made by removing the washer 277 and nut 278 and loosening the screws 282. The bar 274 is then withdrawn from between the loosened screws 282 and turned over, after which the end thereof is replaced between said set screws 282 and the bar 274 secured to its respective carriage by reestablishing the support afforded by the washer 277 and nut 278. The follower plates 269 and 270 will then be disposed, as shown by broken lines in Fig. 14, in horizontally aligned relation with reference to the template 108.

As shown in Fig. 14, it will be noted that the socket 285 in each flanged bar 274 is eccentrically located with reference to the normal longitudinal axis of the bar. This amount of eccentricity is substantially equal to half the thickness of either template 107 or 108 and when said amount or distance is doubled, as by turning the bar over, the peripheral edges of the plates 269 and 270 are raised or lowered, as the case may be, to properly position said edges with reference to either the upper template 107 or the lower template 108.

To completely replace the templates 107 and 108 with other templates of differing outline, the securing screws for the cover plate 103 are removed and said plate is lifted from the floor 33 of the platform 21. In raising the plate 103 in a vertical direction, the keys 118 in the plate 106 are withdrawn from the keyways 120 in the shaft 95 and separate the spindle assembly 31. To accommodate the opening 35 for varying sizes of templates, diametrically disposed notches 366 (Fig. 7) are provided in the peripheral edge of said opening. The screws 115 are threaded from the plates 105 and 106, and the new templates secured together by similar screws 116 and, when again interposed between the plates 105 and 106, are rigidly connected in the assembly by replacement of the screws 115.

Having changed the templates, it is very often necessary and desirable to change the work block 141 and replace it with a block of a form more complementary to the new template outline. This is accomplished by removing the screws 145 from the block 141 so that it can be lifted from the end 137 of the shaft 96. When the block is so removed, the locator fingers 156 will be separated from the notches 158 of the block. When the substitute block has been placed on the shaft, the fingers 156 may be inserted and aligned in the similarly disposed notches of the new block since they are slidably within reasonable limits within the notches 161 of the plate 142. Obviously, a drastic change of template form will necessitate the substitution of the plate 142 as well as the block 141. These changes, which may be effected very conveniently and quickly, are made possible by removal and replacement of the shaft 96 and the cover plate 103 without interference with other associated parts of the machine. When the shaft has been inserted through the opening 35, said shaft 96 is reunited with the shaft 95 when the keys 118 reenter the keyways 120.

It will of course be appreciated that the present invention is not limited to the use of grinding wheels having any particular edge contour. Thus, as illustrated, by way of example, in Figs. 1 and 14, the grinding wheel G is provided with a straight edge, while the edge of the grinding wheel H is beveled. However, in Fig. 23, there is shown a modified arrangement wherein the grinding wheels are designated 368 and 369 and the work piece 370. The peripheral edge of the grinding wheel 368 is beveled as at 371 to bevel the upper corner of the work piece as at 372. On the other hand, the peripheral edge 373 of the grinding wheel 369 is straight as at 374 to grind the flat edge portion 375 of the work piece. The wheel 369 is further provided at its lower edge with a beveled flange 376 which serves to knock off the lower rough corner 377 of the work piece.

It is to be understood that the form of the invention herewith shown and described is to be taken as the preferred embodiment of the same, and that various changes in the shape, size and arrangement of parts may be resorted to without departing from the spirit of the invention or the scope of the subjoined claims.

We claim:

1. In an edge grinding machine of the character described, a rotary work holder comprising a vertically stationary support block for supporting a work piece thereon, a grinding unit comprising a rotary grinding wheel for grinding the edges of the work piece, vertically movable means

for raising the finished work piece from the work holder and for subsequently lowering a rough work piece into position thereon, means for creating a vacuum within the work holder to maintain the work piece in position thereon during grinding, and means under the control of an operator for substantially simultaneously breaking said vacuum and raising the finished work piece from the work holder to facilitate removal thereof and for subsequently lowering a rough work piece onto the work holder and reestablishing the vacuum.

2. In an edge grinding machine of the character described, a rotary work holder comprising a vertically stationary support block for supporting a work piece thereon, a grinding unit comprising a rotary grinding wheel for grinding the edges of the work piece, a drive motor for the work holder, a starter switch for said motor, vertically movable means for lifting the finished work piece from the work holder and for subsequently lowering a rough work piece into position thereon, means for creating a vacuum within the work holder to retain the work piece in position thereon during grinding, and means under the control of an operator for substantially simultaneously rendering the vacuum means ineffective and raising the finished work piece from the work holder to facilitate removal thereof and for subsequently lowering a rough work piece onto the work holder, reestablishing the vacuum and actuating the starter switch to start the drive motor.

3. In an edge grinding machine of the character described, a rotary work holder for supporting a work piece thereon, a vertical shaft carrying the work holder at its upper end, a template carried by said shaft, a pair of grinding units including rotary grinding wheels, rotatable follower plates carried by the grinding units, means for driving the grinding wheels, means for driving said shaft and work holder, means for normally urging the grinding units inwardly to bring the grinding wheels into engagement with the edges of the work piece and the follower plates into engagement with the template, and means for rendering the last-named means effective to cause the grinding units to move inwardly and subsequently ineffective to cause movement of the grinding units outwardly at the completion of the grinding operation, comprising a cam freely rotatable upon said work holder shaft, follower rolls carried by the grinding units and engaging said cam, and means for rotating the cam first in one direction and then the other to cause the grinding units to move inwardly and outwardly.

4. In an edge grinding machine of the character described, a rotary work holder for supporting a work piece thereon, a vertical shaft carrying the work holder at its upper end, a template carried by said shaft, a pair of grinding units including rotary grinding wheels, rotatable follower plates carried by the grinding units, means for driving the grinding wheels, means for driving said shaft and work holder, means for normally urging the grinding units inwardly to bring the grinding wheels into engagement with the edges of the work piece and the follower plates into engagement with the template, means for rendering the last-named means effective to cause the grinding units to move inwardly and subsequently ineffective to cause movement of the grinding units outwardly at the completion of the grinding operation, comprising a cam freely rotatable upon said work holder shaft, follower

rolls carried by the grinding units and engaging said cam, a second rotatable cam, drive connections between said second cam and first cam, and means for driving said work holder shaft and second cam with the relative speeds of rotation thereof being so related that the shaft will rotate more than one full revolution while the second cam rotates one complete revolution to cause an overlapping between the starting and completion points of the grinding operation before the grinding units are moved outwardly.

5. In an edge grinding machine of the character described, a rotary work holder for supporting a work piece thereon, a grinding unit comprising a rotary grinding wheel for grinding the edges of the work piece, a drive circuit including a drive motor, a starting switch and a control switch, means under the control of an operator for momentarily closing the starter switch to complete the circuit and initiate operation of the motor to rotate the work holder, means for opening said control switch to break the circuit at the completion of the machine cycle to stop the work holder, and a timer in said circuit actuated upon closing of the starter switch to maintain the circuit closed until the control switch is subsequently closed.

6. In an edge grinding machine of the character described, a rotary work holder for supporting a work piece thereon, a grinding unit including a rotary grinding wheel for grinding the edges of the work piece and movable toward and away from the same, a pair of templates secured in face to face relation for controlling the extent of grinding of the work piece, a rotary follower plate, a reversible mounting means for supporting said follower plate on said grinding unit in alignment with one of said templates when said supporting means is in one position, said mounting means including a member attachable to and reversible on said grinding unit and that is offset from the plane of rotation of the follower plate so that said follower plate will fall into alignment with the other of said templates when said supporting means is reversed, and means normally urging said grinding unit toward and the grinding wheel into engagement with the work piece and said follower plate into contact with one of said templates.

7. In an edge grinding machine of the character described, a rotary work holder comprising a vertically stationary support block having a surface for supporting a work piece, vertical locator fingers located in surrounding relation to said support block, means mounting said fingers in said location and for vertical movement from a position in which the tops of the fingers are below the work supporting surface on said support block to a position in which the fingers are above said surface, means for creating a vacuum within the work holder to maintain the work piece upon the support block during grinding, and means for raising said fingers into said second mentioned position to receive a work piece to be ground and for subsequently lowering said fingers into said first mentioned position to bring said work piece to rest upon the support block and substantially simultaneously actuating said vacuum creating means to maintain the work piece upon the support block during grinding.

8. In an edge grinding machine of the character described, a rotary work holder for supporting a work piece thereon, a grinding unit comprising a rotary grinding wheel for grinding the edges of the work piece and movable toward and

away from the same, a vertical shaft carrying the work holder at its upper end, a template substantially conforming to the periphery of the work piece and carried by said shaft, a rotatable follower plate carried by the grinding unit, drive means for said shaft, means urging the grinding unit inwardly and the grinding wheel and follower plate into engagement with the work piece and template respectively, and means for moving the grinding unit outwardly and the grinding wheel and follower plate from contact with the work piece and template after the work holder has completed a predetermined amount of rotation.

9. In an edge grinding machine of the character described, a rotary work holder for supporting a work piece thereon, a grinding unit comprising a rotary grinding wheel for grinding the edges of the work piece and movable toward and away from the same, a vertical shaft carrying the work holder at its upper end, a template substantially conforming to the periphery of the work piece and carried by said shaft, a rotatable follower plate carried by the grinding unit, drive means for said shaft, means normally urging the grinding unit inwardly and the grinding wheel and follower plate into engagement with the work piece and template respectively, means automatically actuated by said drive means for moving the grinding unit outwardly and the grinding wheel and follower plate from contact with the work piece and template after the work holder has completed at least one full revolution, and a switch automatically actuated by said last-named means to render said drive means ineffective to thereby stop the rotation of said shaft and the outward movement of the grinding unit.

10. In an edge grinding machine of the character described, a rotary work holder for supporting a work piece thereon, a vertical shaft carrying the work holder at its upper end, a template
